UNITED STATES PATENT OFFICE.

THOMAS JAMES RAYNER, OF LONDON, ENGLAND.

EVAPORATING APPARATUS.

SPECIFICATION forming part of Letters Patent No. 519,969, dated May 15, 1894.

Application filed November 27, 1893. Serial No. 492,159. (No model.) Patented in England May 31, 1893, No. 10,700.

To all whom it may concern:

Be it known that I, THOMAS JAMES RAYNER, a citizen of England, residing at 777 Commercial Road, Limehouse, in the city of London, England, have invented a new and useful Improvement in Evaporating Apparatus, (for which I have obtained a patent in Great Britain, dated May 31, 1893, No. 10,700,) of which the following is a specification.

10 In my Patent No. 468,048, dated February 2, 1892, I described a surface condenser.

The object of my present invention is to adapt the apparatus for evaporating liquids, and to accomplish this object my invention 15 consists in the features of construction and the combination or arrangement of parts hereinafter described and claimed, reference being made to the accompanying drawings, in which—

20 Figure 1 is a vertical section on Y Y of Fig. 2 which is a plan on X X of evaporating apparatus according to my invention.

A is a cylindrical vessel containing the liquid to be evaporated and having a cover B with connections C C for a vapor pipe and safety valve, the latter being provided for the escape of vapor when the pressure becomes too great. In the lower part of the vessel A there is a lateral opening having a removable 25 cover D secured by bolts and nuts. In this cover are formed several passages F', F², F³, F⁴, the uppermost F' having a connection for a steam supply pipe, and the lowest F⁴ having a connection of a condensed water pipe. 30 About the middle of the vessel there is a pedestal G on which rests a connecting piece E in which are formed passages H' H² H³. A number of spirally bent pipes K' K², &c., connect the passages F in the cover D with the 35 passages H in the casting E. Steam admitted to F' passes by the spiral pipe K' to the passage H' thence by pipe K² to F², from F² by pipe K³ to H² and so on finally reaching F⁴ in a more or less condensed state. The connecting piece E may be made in three sepa- 45

rate parts each for one of the passages H. The liquid to be evaporated is charged into the cylindrical vessel A in any suitable manner, preferably as disclosed by my patent above referred to. The heat vaporizes the liquid 50 surrounding the pipes K, and the vapor rises to the top of the vessel frequently mingled with portions of the liquid carried up by ebullition. In order to prevent the liquid so carried up from passing away by the vapor, I 55 suspend from the cover B an inverted cup L to which is attached by brackets M a conical shell N the lower edge of which nearly touches the interior surface of the vessel A. The vapor passes up through the opening at the top 60 of the shell N and is deflected downward by the cup L as indicated by the arrows, the liquid being thus separated from it and deposited on the upper surface of N whence it descends along the interior surface of A to the 65 liquid therein. As before stated, the lower edge of the shell N, which is in the form of a truncated cone, nearly touches the internal surface of the cylindrical vessel, whereby the condensed liquid is permitted to trickle down, 70 but the main portion of the vapor is compelled to pass up through the center of the shell. This construction and arrangement is advantageous, and provides a very simple and efficient means, whereby the apparatus is 75 adapted for evaporating liquids. When the pipes K require to be cleaned or repaired, the cover D is unbolted and removed bringing with it the pipes K and their connecting piece E the whole of the heating surface as well as 80 the interior of the vessel A being thus made accessible.

Having thus described the nature of this invention and the best means I know of carrying the same into practical effect, I claim— 85

An evaporating apparatus, consisting of a vessel A, a series of convolute coils of pipes communicating with one another for the passage of steam therethrough and located in the lower portion of the vessel, a shell N formed 90

- as a truncated cone and having its lower edge nearly touching the internal surface of the vessel, so that the condensed liquid can trickle down while the main portion of vapor is compelled to pass up through the center of the shell, and an inverted cup L suspended from the top portion of the vessel and arranged over the said shell, substantially as and for the purposes described.
- 10 In testimony whereof I have signed my name to this specification, in the presence of

two subscribing witnesses, this 10th day of November, A. D. 1893.

THOMAS JAMES RAYNER.
